E. J. Clarkson,
Attorney

UNITED STATES PATENT OFFICE.

LUKE S. STRIPLING, OF BURKBURNETT, TEXAS, ASSIGNOR OF ONE-HALF TO ROBERT L. GRAGG, OF BURKBURNETT, TEXAS.

WINDMILL.

Application filed June 3, 1926. Serial No. 113,486.

This invention relates to windmills and has special reference to a windmill wherein the wings revolve about a vertical axis.

One object of the invention is to improve 5 the general construction of devices of this character.

A second important object of the invention is to provide an improved form of wing for such windmill.

10 A third important object of the invention is to provide a windmill construction wherein the wind power will be exerted in an improved and highly efficient manner.

A fourth important object of the invention 15 is to provide an improved and novel form of shutter arrangement for the wings of such a windmill.

A fifth important object of the invention 20 is to provide an improved arrangement for controlling the effective area of the wings in such a windmill.

25 A sixth important object of the invention is to provide a novel arrangement wherein the wings are arranged in pairs, the wings of each pair being provided with means for simultaneously controlling their effective areas.

30 A seventh important object of the invention is to provide a novel arrangement of sets of wings of improved character, the arrangement being such that each set has its wings brought into operative position at equal intervals, the wings of the several sets also being brought successively into operative position at equal intervals.

35 An eighth important object of the invention is to provide an improved and novel form of pump jack for use in connection with this windmill.

40 With the above and other objects in view as will be hereinafter apparent, the invention consists in general of certain novel details of construction and combinations of parts hereinafter fully described, illustrated 45 in the accompanying drawings and specifically claimed.

In the accompanying drawings like characters of reference indicate like parts in the several views, and:

50 Figure 1 is a side elevation of a windmill tower showing the invention applied thereto, certain of the parts being broken away.

Figure 2 is an enlarged side elevation of one of the wings, the view being from the rear thereof.

55

Figure 3 is an enlarged detail section on the line 3—3 of Figure 2.

Figure 4 is an enlarged detail section on the line 4—4 of Figure 1.

Figure 5 is a plan view of the bottom plate 60 of a ball thrust bearing used herewith.

Figure 6 is a transverse section taken diametrically through said ball bearing.

Figure 7 is a top view of the pump jack.

Figure 8 is a side elevation of said pump 65 jack.

Figure 9 is a detail elevation of a portion of the main drive shaft.

While a tower or derrick has been shown in the accompanying drawings much of the 70 bracing has been omitted for the sake of clearly disclosing the invention itself.

It is not to be understood that such omission of bracing is necessary as the invention is not limited to application to any particular form of tower but I may use any tower which I may find to be of suitable strength and construction. Furthermore certain details such as bearings and the like have been shown and will be described in order that 75 the invention may be understood. I do not limit myself, however, to the exact form of constructional details of this character here shown and described since I may use such types of bearings and the like as I may find 80 expedient in any particular case.

Again, while it will be found that the invention as described calls for five sets of wings with four wings in each set, such invention is broader than any particular numbers of sets or wings and I am not to be confined to the numbers I find at this time to be 85 most expedient.

In the embodiment of the invention here disclosed there is shown a tower or derrick 90 having upright corner posts 10 supporting a platform 11 at the top. This top is reached by a suitable stair 12. These parts may be of any desired material and shape and a useful material for the posts is found to be 95 steel angle bars. Supported on the platform is a bearing 13 and adjacent the bottom of the tower is a ball bearing of the thrust type. This latter bearing consists of a bot- 100

tom plate 14 provided with ball grooves 15 in which are held balls 16. On these balls rests an upper plate 17 having a collar 18 which is firmly secured to the power shaft 19. This shaft is also journalled in the bearing 13 and other intermediate bearings, such as is shown at 20 may be provided for long shafts and high towers. Preferably the plate 14 is made of suitable hard steel and 10 is square in form so that bars 21 may be bolted thereto, as shown in Figure 5, and extend diagonally to the corner posts 10 and there be firmly secured. Braces 22 may also be used to render the structure rigid and 15 thus provide a firm support for the bearing. The intermediate bearing may be supported in like manner if desired. Projecting up from the fixed plate 14 is a pivot pin 23 whereon is pivoted a brake lever 24 having one end bearing against the shaft 19 and its 20 other end working over a notched bar 25 of the type usual for holding such levers in adjusted position.

Mounted on the foundation 26 are suitable 25 standards 27 which support horizontally alined bearings 28 wherein is journalled the main drive shaft 29. On the lower end of the shaft 19 is a bevel pinion 30 which meshes with a bevel gear 31 fixed on the 30 shaft 29. On one end of the shaft 29 is a bevel pinion 32 which meshes with a bevel gear 33 fixed on a shaft 34 by means of which power may be transmitted to any desired machinery. Also one or more belt or 35 band wheels 35 may be fixed on the shaft 29.

Fixed on the portion of the shaft 19 which projects above the platform 11 is a series of spaced center plates 36 each having a collar 37 projecting from its underside. This collar surrounds and is securely bolted to the shaft. I have found that it is best to use five of these plates and their accompanying parts but I have here indicated but two of such 40 plates with their accompanying parts as it is deemed unnecessary to extensively duplicate these parts in the drawings and the invention can be well understood without such showing. From each center plate radiates arms 38, preferably four in number and arranged in right angularly disposed pairs so that the arms are evenly spaced circumferentially. The arms of each plate are displaced angularly with respect to the arms of the plate next below one fifth of a circle 45 or seventy-two degrees. Bolted to each of the arms is a horizontally extending wing frame 39 and through the vertical ends of each frame extends a shutter rod 40. On each rod is swingingly mounted a series of 50 shutter leaves or vanes 41. The rod 40 is arranged near the top of the respective frame and extends through suitable thickened portions near the tops of the leaves so that the normal tendency of these leaves is 55 to hang vertically. In the bottom member

of the frame is a rabbet 42 which receives the lower ends of the leaves when in vertical position and these leaves bear against the vertical side of this rabbet when in fully closed position and acted on by the wind. 60 Thus the leaves are limited in movement in one direction. These leaves can swing from vertical to horizontal position, as they do when the windmill revolves and the wind is blowing against the backs of the leaves. In 65 order to limit the lift of the leaves stop lugs 43 are provided on the upper member of the frame. In the larger sizes of windmills it is advisable to support the shutter rods intermediate their ends and for this purpose a 70 bracket 44 having depending bearing ends may be fixed to the frame. A trip bar 45 extends along the front of each series of leaves and is provided with upturned ends 46 fixed securely to the shutter rod. Fixed 75 on the inner end of each shutter rod 40 is a rock arm 47 to which is connected one end of a pull cable 48. These pull cables are 80 connected in pairs to rings 49 provided with hand grips 50. The cables connected to each 85 ring extend to the rock arms of diametrically disposed wings and lead through cable guides on a table 51 fixed to the shaft 19. Thus by pulling on a hand grip opposite 90 series of leaves may be raised to partially or fully open position as desired and the effective area of the wings diminished to any 95 desired extent. This adjustment is not only useful when it is desired to stop the windmill (in which case all the trip rods are 100 raised) but is also useful when it is desired to reduce the speed and especially when high winds are blowing.

In order to prevent too great movement 105 of the trip bar and to brace the same at the middle, a brace 47' is fixed to the top and bottom members of the frame to the rear of said trip bar.

In order to produce even and smooth motion of the device and to prevent the variations in speed frequently noticed in windmills when gusty winds are blowing, there is provided on the shaft a collar 51 firmly fixed to said shaft and supporting a pair of arms 52 carrying pins 53 which pass through 110 slots 54 formed in governor arms 55. These arms are pivoted at their upper ends to a collar 56 slidably mounted on the shaft 19 and have at their lower ends heavy governor 115 balls 57 by which the collar is normally held raised. These balls, upon increase of speed move outwardly and upwardly and thus, through their fly wheel effect, tend to regulate the speed and cause the device to 120 reverse evenly.

On the remaining end of the shaft 29 is fixed a crank disk 58 carrying a crank pin 59. This disk and pin are used for converting the rotary motion of the shaft 29 to reciprocating motion such as is used in connec- 125 130

tion with my pump jack which will now be described.

This pump jack includes a U-shaped frame having a base 60 securely clamped to the upper end of a casing 61 and projecting upwardly from this casing to move up and down therein is a sucker rod 62 having a series of spaced holes 63 in its upper end. A headed pin 64 is provided which may be inserted in any desired hole 63 and is suitably secured by a cotter pin so that the pin cannot slip out. It may be here noticed that all other pins are provided with suitable cotters for the same purpose. On the pin 64 is pivoted one end of a link 65 which has its other end pivoted to the crank pin 59 and it is to be noticed that this crank pin may be mounted in any one of a series of holes 66 in the disk 58 so that the throw of the crank 75 may be thus adjusted to suit desired movements of the sucker rod 62. At each end of the base portion 60 is an upright arm 67 which carries at its upper end a pin 68 whereon is pivoted a lever 69, the lever having a series of holes 70 therein so that the lever may be selectively positioned on the pin. The inner ends of these levers carry pins 71 on which are pivoted the forked links 72 which have their forked ends straddling the upper end of the sucker rod and are pivotally connected thereto by a pin 73 passing through one of the holes 63. Slidably mounted on the levers 69 are weights 74 which are secured in desired positions by pins 75 passing through selected holes 70. Thus these weights assist in counterbalancing the weight of the sucker rod. On top of the casing 61 rests a plate 76 and above this is a second plate 77 which is held from sliding up on the sucker rod by a pin 78 which may be inserted through any desired opening 63 to properly tension the coiled spring 79 surrounding the sucker rod between these plates. A third plate 80 is similarly positioned by a pin 81 and between the second and third plates is a coiled spring 82. The base 60 is provided with clamp bolts 83 and these bolts carry the lower ends of zig-zag springs 84 which have their upper ends firmly secured to the plate 80. By means of this arrangement the weight of the sucker rod is properly balanced and the pump operated with very little loss of power.

It is to be noted that lips 43' are turned up on the wing between the stops 43 to deflect the wind downwardly.

It will be noted, also, that the weights 74 are the means of entirely balancing the sucker rod weight in all open field, farm or ranch pumps but where space is a consideration the supplementary aid of adjustments in springs 79 and 82 by means of manipulating springs 79 and 82 to a greater upward tension thereby lessening the necessary

length of levers 69 and the size of weights 74 which may be necessary in engine rooms or between close walls.

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come within the scope claimed.

Having thus described the invention, what is claimed as new, is:

1. In a windmill, a wing including a frame, a shutter rod extending longitudinally of the frame adjacent the upper part thereof, a series of shutter leaves mounted on said rod to swing relative thereto, means to limit the swinging movement of said leaves, a trip bar engaging the rear faces of the leaves, means to support the trip bar for swinging movement about an axis adjacent the top of the frame, a rock arm operatively connected to the trip bar for swinging the same, and a pull cable connected to the rock arm.

2. In a windmill, a rectangular frame having its longer axis horizontal, a shutter rod journaled in the ends of the frame near the top thereof, a series of leaves mounted on said rod for swinging movement relative thereto, a rabbet in the lower portion of the frame into which the lower ends of the leaves engage when closed, said series of leaves closely filling the space within said frame when closed, and stops on the upper part of the frame engaging the leaves when fully opened to limit upward swinging movement of said leaves.

3. In a windmill, a rectangular frame having its longer axis horizontal, a shutter rod journaled in the ends of the frame near the top thereof, a series of leaves mounted on said rod for swinging movement relative thereto, a rabbet in the lower portion of the frame into which the lower ends of the leaves engage when closed, said series of leaves closely filling the space within said frame when closed, stops on the upper part of the frame engaging the leaves when fully opened to limit upward swinging movement of said leaves, and manually controlled means to regulate the extent of closing of said leaves.

4. In a windmill, a rectangular frame having its longer axis horizontal, a shutter rod journaled in the ends of the frame near the top thereof, a series of leaves mounted on said rod for swinging movement relative thereto, a rabbet in the lower portion of the frame into which the lower ends of the leaves engage when closed, said series of

leaves closely filling the space within said frame when closed, stops on the upper part of the frame engaging the leaves when fully opened to limit upward swinging movement 5 of said leaves, a trip bar extending longitudinally of the frame and normally positioned within the frame for engagement by the rear faces of the leaves when closed, arms projecting upwardly from the ends of 10 the trip bar and having their upper ends fixed on the shutter rod, a rock arm fixed in one end of the shutter rod, and a manually operable pull cable having one end fixed to the free end of the rock arm.

15 5. In a windmill having a vertical shaft supported for free revolution, a series of horizontal wing frames radiating from and fixed on the shaft at equally spaced intervals, shutter rods each extending longitudinally of a respective frame, series of shutter leaves, each series being mounted on a respective rod to swing between vertical and horizontal positions relative thereto, means on each frame for limiting the swinging 20 movement of the series of leaves thereby, means for raising each series from vertical towards horizontal position, and manually controlled means for simultaneously operating each pair of opposite wings of the 25 series.

30 6. In a windmill having a vertical shaft supported for free revolution, a plurality of vertically spaced sets of wings, each set including a series of horizontal wing frames radiating from and fixed on the shaft at equally spaced intervals, shutter rods each extending longitudinally of a respective frame, series of shutter leaves, each series being mounted on a respective rod to swing 35 between vertical and horizontal positions relative thereto, means on each frame for limiting the swinging movement of the series of leaves thereby, means for raising each series from vertical towards horizontal 40 position, and manually controlled means for simultaneously operating each pair of opposite wings of the series, each set of wings being circumferentially displaced relative to the adjacent sets.

45 7. In a windmill having a vertical shaft supported for free revolution, a plurality of vertically spaced sets of wings, each set including a series of horizontal wing frames radiating from and fixed on the shaft at 50 equally spaced intervals, shutter rods each extending longitudinally of a respective frame, series of shutter leaves, each series being mounted on a respective rod to swing between vertical and horizontal positions relative thereto, means on each frame for limiting the swinging movement of the series of leaves thereby, means for raising each series from vertical towards horizontal 55 position, and manually controlled means for simultaneously operating each pair of opposite wings of the series.

60 8. In a windmill having a vertical shaft supported for free revolution, a series of horizontal wing frames radiating from and fixed on the shaft at equally spaced intervals, shutter rods each extending longitudinally of a respective frame, series of shutter leaves, each series being mounted on a respective rod to swing between vertical and horizontal positions relative thereto, means on each frame for limiting the swinging movement of the series of leaves thereby, each frame also having a trip bar engaging the rear faces of the leaves, means to support the trip bar for swinging movement about an axis adjacent the top of the frame, a rock arm operatively connected to the trip bar swinging the same, and a pull cable connected to the rock arm.

65 9. In a windmill having a vertical shaft supported for free revolution, a series of horizontal wing frames radiating from and fixed on the shaft at equally spaced intervals, shutter rods each extending longitudinally of a respective frame, series of shutter leaves, each series being mounted on a respective rod to swing between vertical and horizontal positions relative thereto, means on each frame for limiting the swinging 70 movement of the series of leaves thereby, each frame also having a trip bar extending longitudinally of the frame and normally positioned within the frame for engagement by the rear faces of the leaves when closed, arms projecting upwardly from the ends of 75 the trip bar and having their upper ends fixed on the shutter rod, a rock arm fixed in one end of the shutter rod, and a manually operable pull cable having one end fixed to the free end of the rock arm.

80 10. In a windmill having a vertical shaft supported for free revolution, a series of horizontal wing frames radiating from and fixed on the shaft at equally spaced intervals, shutter rods each extending longitudinally of a respective frame, series of shutter leaves, each series being mounted on a respective rod to swing between vertical and horizontal positions relative thereto, means on each frame for limiting the swinging 85 movement of the series of leaves thereby, each frame also having a trip bar extending longitudinally of the frame and normally positioned within the frame for engagement by the rear faces of the leaves when closed, arms projecting upwardly from the ends of the trip bar and having their upper ends fixed on the shutter rod, a rock arm fixed in one end of the shutter rod, and a manually operable pull cable having one end fixed to the free end of the rock arm.

90 11. In a windmill having a vertical shaft supported for free revolution, a plurality of horizontal wing frames radiating from and fixed on the shaft at equally spaced intervals, shutter rods each extending longitudinally of a respective frame, series of shutter leaves, each series being mounted on a respective rod to swing between vertical and horizontal positions relative thereto, means on each frame for limiting the swinging movement of the series of leaves thereby, means for raising each series from vertical towards horizontal position, manually controlled means for simultaneously operating each pair of opposite wings of the series, and a governor carried by said shaft to prevent sudden variations in the speed thereof.

120 12. In a windmill having a vertical shaft supported for free revolution, a plurality of

vertically spaced sets of wings, each set including a series of horizontal wing frames radiating from and fixed on the shaft at equally spaced intervals, shutter rods each 5 extending longitudinally of a respective frame, series of shutter leaves, each series being mounted on a respective rod to swing between vertical and horizontal positions relative thereto, means on each frame for 10 limiting the swinging movement of the series of leaves thereby, means for raising each series from vertical towards horizontal position, manually controlled means for simultaneously operating each pair of opposite 15 wings of the series, each set of wings being circumferentially displaced relative to the adjacent sets, and a governor carried by said shaft to prevent sudden variations in the speed thereof.

12. In a windmill having a vertical shaft supported for free revolution, a plurality of vertically spaced sets of wings, each set including a series of horizontal wing frames radiating from and fixed on the shaft at 20 equally spaced intervals, shutter rods each extending longitudinally of a respective frame, series of shutter leaves, each series being mounted on a respective rod to swing between vertical and horizontal positions relative thereto, means on each frame for 25 limiting the swinging movement of the series of leaves thereby, means for raising each series from vertical towards horizontal position, manually controlled means for simultaneously operating each pair of opposite 30 wings of the series, each set of wings being circumferentially displaced relative to the adjacent sets, and a governor carried by 35 said shaft to prevent sudden variations in the speed thereof.

13. In a windmill having a vertical shaft 40 whereby to produce equal power in all positions of said sets, and a governor carried by said shaft to prevent sudden variations in the speed thereof.

45. 13. In a windmill having a vertical shaft

supported for free revolution, a series of horizontal wing frames radiating from and fixed on the shaft at equally spaced intervals, shutter rods each extending longitudinally of a respective frame, series of shutter 50 leaves, each series being mounted on a respective rod to swing between vertical and horizontal positions relative thereto, means on each frame for limiting the swinging movement of the series of leaves thereby, 55 each frame also having a trip bar engaging the rear faces of the leaves, means to support the trip bar for swinging movement about an axis adjacent the top of the frame, a rock arm operatively connected to the trip bar swinging the same, a pull cable connected to the rock arm, and a governor carried by 60 said shaft to prevent sudden variations in the speed thereof.

14. In a windmill having a vertical shaft 65 supported for free revolution, a series of horizontal wing frames radiating from and fixed on the shaft at equally spaced intervals, shutter rods each extending longitudinally of a respective frame, series of shutter 70 leaves, each series being mounted on a respective rod to swing between vertical and horizontal positions relative thereto, means on each frame for limiting the swinging movement of the series of leaves thereby, 75 each frame also having a trip bar extending longitudinally of the frame and normally positioned within the frame for engagement by the rear faces of the leaves when closed, arms projecting upwardly from the ends of 80 the trip bar and having their upper ends fixed on the shutter rod, a rock arm fixed in one end of the shutter rod, a manually operable pull cable having one end fixed to the free end of the rock arm, and a governor 85 carried by said shaft to prevent sudden variations in the speed thereof.

In testimony whereof I affix my signature.

LUKE S. STRIPLING.
